[57] CLAIM

The ornamental design for a bench top table saw, as shown.

DESCRIPTION

FIG. 1 is an isometric view of the bench top table saw of the present invention;

FIG. 2 is a front elevational view of the bench top table saw illustrated in FIG. 1;

FIG. 3 is a rear elevational view of the bench top table saw illustrated in FIG. 1;

FIG. 4 is a right side elevational view of the bench top table saw illustrated in FIG. 1;

FIG. 5 is a left side elevational view of the bench top table saw illustrated in FIG. 1;

FIG. 6 is a top view of the bench top table saw illustrated in FIG. 1; and,

FIG. 7 is a bottom view of the bench top table saw illustrated in FIG. 1.

FIG. 2

FIG. 3

FIG. 4

FIG. 5

FIG. 6
